UNITED STATES PATENT OFFICE.

FRANK CURTIN, OF GLOVERSVILLE, NEW YORK, ASSIGNOR TO CURTIN-HEBERT COMPANY, INC., OF GLOVERSVILLE, NEW YORK, A CORPORATION OF NEW YORK.

HOSIERY-TIPPING PLATE.

1,349,410.

Specification of Letters Patent. Patented Aug. 10, 1920.

Application filed November 19, 1919. Serial No. 339,083.

To all whom it may concern:

Be it known that I, FRANK CURTIN, a citizen of the United States, residing at Gloversville, county of Fulton, and State of New York, have invented a new and useful Improvement in Hosiery-Tipping Plates, of which the following is a full, clear, and exact description, reference being had to the accompanying drawings, which form a part of this specification.

In the manufacture of the high grades of hosiery it is customary to cut the stocking out of a piece of knitted fabric in two sections. The heel and toe portions are reinforced, on the inside, with additional pieces of the fabric and the two sections joined together by seams.

In securing the reinforcements, it is desirable that they be secured in such manner that the stitches at the point of junction with the body of the fabric be relatively invisible on the outside of the stocking.

The methods heretofore used in securing the reinforcements have failed to produce the desired invisibility of stitch and are so slow as to seriously impair economic production of hosiery of this character.

My invention has for its object to provide means to hold the stocking sections and reinforcements and feed them to the sewing machine in such a manner as to insure the accuracy and relative invisibility of the stitch and which, at the same time, will permit of the work being done with a maximum of speed, by comparatively unskilled hands, and greatly increase production.

The device involving my invention may be readily adapted to any suitable sewing machine, as, for example, the Brosser or Polmateer over-stitch machines.

I will now proceed to describe my invention in detail with reference to the accompanying drawings, in which I have illustrated a preferred embodiment thereof and in which like symbols refer to like parts in the various views.

Figure 1 is a plan view of the upper part of the foot portion and the heel of a stocking.

Fig. 2 is a plan view of the lower part of the foot portion of a stocking.

Fig. 3 is a plan view of a reinforcing piece for the toe.

Fig. 4 is a plan view of a reinforcing piece for the heel.

Fig. 5 is a horizontal elevation of my hosiery tipping plate associated with a part of the sewing machine.

Fig. 6 is an end view partly in section of the same.

Fig. 7 is a diagrammatic sectional view of my hosiery tipping plate with the goods in place for stitching.

Referring to Figs. 1-4: The stocking is finished by folding the piece *a* on the line *b*-*b*, sewing the edges of the upper foot piece *c* to the edges of the lower foot piece *d*, and the edges of the heel sections *e* to each other and to the rear of the lower foot piece; the leg section, not shown, is then seamed up. Before finishing the stocking, the heel is reinforced by securing a reinforcing piece *f* to each of the heel sections *e* along the line *g*-*g*, while the toe is reinforced by securing a reinforcing piece *h* to each of the toe sections *i* along the lines *j*-*j*. The free ends of the reinforcing pieces are secured in the seams joining the heel and toe sections together.

Referring to Figs. 5-7: To a plate *k* preferably made of aluminum is secured a stiffening strip *l*, flush with its lower edge. Opposite to the strip *l* and spaced from the lower edge of the plate is secured a horizontally extending rack bar *m*. A thin top plate *n* having a straight edge, partially beveled, is secured to the upper portion of the plate *k*, the plate being bent back to permit the top plate to lie flush with the plate *k*. Adjacent the straight edge *n* a stiffening strip *o* is secured to the top plate. Rows of pins *p*, *p'*, extending laterally from the top plate, extend horizontally, one row on each side thereof.

A cover *q*, extending from the rack bar to a point adjacent one of the rows of pins *p* and forming a pocket with the plate *k*, is hinged to the top of the rack bar. A series of clamps *r* extending above one of the rows of pins *p'* are hinged to the plate *k* opposite to the cover *q*. Each clamp is provided at its lower end with a tail *s*, extending through an aperture *t* in the plate, into contact with a flat spring *u* secured to the plate and adapted to force the upper edge of the clamp *r* against the top plate.

In Figs. 5 and 6 I have illustrated the attachment of my tipping plate to an over-stitch machine of the Brosser horizontal needle type. The lower edge of the plate *k*

rests on the rollers v suitably supported on the frame y of the machine, while the top plate is guided by the cups w , above which it extends slightly, in order that the stitching mechanism, may operate on the goods. A pinion x supported by the machine and suitably driven meshes with the rack bar m and causes the plate to travel horizontally, as the stitching operation progresses.

10 In practice, the cover q is opened out and the body of the stocking section engaged on the pins p . One of the heel sections e is then drawn over the straight edge with some tension so that the line $g-g$ coincides with the edge. The clamps r are retracted and the body of the heel section engaged with the row of pins p' . The heel reinforcement is then placed against the heel section with the edge g', g' adjacent the line $g-g$ of the heel section e on the straight edge. The reinforcement is engaged by the row of pins p' and the clamps r closed to securely hold it in place, all as shown in Fig. 7.

The stocking section is then folded so that 25 the two sections i may be drawn over the straight edge along the line $j-j$ and the reinforcement piece h is positioned relative to the toe in the same manner as the heel portion and its reinforcement.

30 The section d and its toe reinforcement are secured in the plate in the same manner.

The leg portion of the stocking is disposed in the pocket formed by the cover q and the cover g closed. The plate is then 35 placed on the rollers v and pushed forward until the top plate is between the cups w and the pinion x engages the rack. The machine is then started and the plate moves horizontally presenting the work to the 40 needle z .

It will be seen that the fabric is positively held on both sides of the top plate and the tension of the fabric over the edge positively maintained, which, in connecting with the 45 narrowness of the edge, insures that the needle will not penetrate more than one or,

at the most, two threads of the fabric and thus permitting it to secure the reinforcements with a stitch which will be relatively invisible from the outside of the completed stocking. At the same time, the speed with which the reinforcements may be stitched on is greatly increased with resultant increased production.

It will be understood that the plate may be 55 of any convenient length and that a number of heels and toes may be carried in it at one time, the leg portions of the stocking being thoroughly protected by the cover q .

Having now fully described my invention, 60 what I claim and desire to protect by Letters Patent is:

1. The combination with a reciprocable needle, and a traveling plate affording a straight edge movable into operative relation with the needle and over which a fabric may be drawn, of two rows of pins projecting laterally from opposite sides of said plate beneath said straight edge and adapted to engage the fabric and hold it properly 70 positioned and tensioned, one of said rows of pins adapted also to engage a reinforcing piece to afford a definite free length of reinforcing piece extending above the last named row of pins, and a clamp adapted to confine 75 the previously positioned reinforcing piece against that part of the fabric on one side of and adjacent the straight edge.

2. The combination with a hosiery tipping plate having a straight edge, means to engage a fabric on opposite sides of said edge, a cover hinged to said plate and forming a pocket for the fabric, a clamp hinged to said plate opposite to said cover, a tail extending from the lower part of said clamp and extending through an aperture in said plate, and a spring secured to said plate and adapted to act on said tail.

In testimony of which invention, I have hereunto set my hand, at Gloversville, N. Y., 90 on this 15th day of November, 1919.

FRANK CURTIN.
